[57] CLAIM

The ornamental design for a ski, as shown and described.

DESCRIPTION

FIG. 1 is a side elevational view of a ski showing my new design, the side opposite being a mirror image;
FIG. 2 is a top plan view thereof;
FIG. 3 is a bottom plan view thereof;
FIG. 4 is a front elevational view thereof;
FIG. 5 is a rear elevational view thereof;
FIG. 6 is a cross-sectional view thereof taken along line VI—VI in FIG. 2 shown on an enlarged scale;
FIG. 7 is a cross-sectional view thereof taken along line VII—VII in FIG. 2 shown on an enlarged scale;
FIG. 8 is a cross-sectional view thereof taken along line VIII—VIII in FIG. 2 shown on an enlarged scale; and,
FIG. 9 is a perspective view thereof.

FIG.1FIG.3
